(57) **CLAIM**

The ornamental design for “animal grooming brush”, as shown and described.

DESCRIPTION

FIG. 1 illustrates a perspective view of an animal grooming brush showing my new design;

FIG. 2 is a right side elevational view of thereof, the left side being the same as the right side;

FIG. 3 is a bottom plan view thereof; and,

FIG. 4 is a top plan view thereof.

The broken lines shown in FIG. 3 illustrates environmental structure that forms no part of the claimed design. The long dash-short dash broken line shown in FIG. 3 represents the bounds of the claim and forms no part of the claimed design.
